UNITED STATES PATENT OFFICE

ANTON JOSEPH PALME, OF SOUTH ORANGE, NEW JERSEY, ASSIGNOR, BY MESNE ASSIGNMENTS, TO EAGLE PENCIL COMPANY, OF NEW YORK, N. Y., A CORPORATION OF DELAWARE

DESIGN FOR A PENCIL SHARPENER

Application filed October 11, 1930. Serial No. 37,243. Term of patent 14 years.

To all whom it may concern:

Be it known that I, ANTON J. PALME, a citizen of Czechoslovakia, residing at South Orange, in the county of Essex and State of New Jersey, have invented a new, original, and ornamental Design for a Pencil Sharpener, of which the following is a specification, reference being had to the accompanying drawing, forming part thereof.

The illustration is a perspective view of a pencil sharpener, showing my new design.

The configuration of the side of the pencil sharpener not shown is the same as that of the side illustrated.

I claim:

The ornamental design for a pencil sharpener, substantially as shown and described.

ANTON JOSEPH PALME.
